FIG. 3.

UNITED STATES PATENT OFFICE.

GEORGE H. MYRICK, OF CHICAGO, ILLINOIS, ASSIGNOR TO CAPITAL ELECTRIC COMPANY, OF CHICAGO, ILLINOIS, A CORPORATION OF ILLINOIS.

WASHING-MACHINE.

1,186,025

Specification of Letters Patent. Patented June 6, 1916.

Application filed January 23, 1915. Serial No. 3,871.

To all whom it may concern:

Be it known that I, GEORGE H. MYRICK, a citizen of the United States, residing at Chicago, in the county of Cook and State of Illinois, have invented a certain new and useful Improvement in Washing-Machines, of which the following is a full, clear, concise, and exact description, reference being had to the accompanying drawings, forming a part of this specification.

My invention relates to an improved form of washing machine in which the articles to be washed are moved in the solution by means of which they are washed by the projection into and through said articles of a stream of the solution; and in the embodiment of my invention herein-after illustrated, I provide a rotary cylinder for containing the articles to be washed, such as clothing, against which the stream of solution, as water and soap, is projected tangentially or nearly so, by means of a fan or screw propeller. This fan is electrically driven and the motor is arranged to be used to drive a wringer, if desired. Suitable devices of novel construction and arrangement are provided to operatively connect the wringer with the motor when desired. The cylinder employed to contain the fabrics to be washed is of openwork construction so that the water and soap solution projected against the side of the cylinder not only imparts to it a rotary motion, but the solution is also projected through the walls of the cylinder and into and through the fabrics, thus agitating the same and greatly assisting in separating from the fabrics the dirt contained in them.

As will hereinafter be more fully pointed out the rotary cylinder or fabric container is capable of being easily manipulated to move the container to its operating position after the fabrics to be washed have been placed therein, and to move the container to such a position that the clothes may be readily and easily removed therefrom, after the washing operation has been completed. The mechanism whereby this manipulation of the fabric cylinder or container is made possible, comprises broadly a bail-like cylinder lifter and a pair of bearings, or brackets, carried by the washer tank and with which the lifter co-operates. As will be subsequently explained the lifter and brackets referred to are adapted to securely

lock the fabric container in either its raised or operating position. As will hereinafter appear in the use of my improved washing machine, it is essential that after the fabric container has been filled with articles to be washed and submerged in the solution within the washer tank, that the fabric container be locked in operating position inasmuch as the fabrics to be washed, until they are thoroughly soaked, contain a considerable amount of air and tend to float the container. After the washing operation is completed the fabric container is raised from its operating position and is locked in raised position by the mechanism previously referred to. The operator is thus enabled to permit the washed fabrics to drain to a greater or less extent before removing them from the container.

My invention consists in the construction, arrangement and combination of parts fully set forth in the following detailed description in which reference is made to the accompanying drawings.

In the drawings, Figure 1 is a rear elevational view of the improved washing machine of my invention, certain parts being illustrated in section to more clearly reveal the construction, Fig. 2 is a cross-sectional view taken on the line 2, 2, of Fig. 1, and looking in the direction indicated by the arrows, Fig. 3 is a view partly in section and partly in elevation taken on the line 3, 3, of Fig. 2, and looking in the direction indicated by the arrows, Fig. 4 is a fragmentary detailed view illustrating how the fabric container is locked in raised position, Fig. 5 is a fragmentary sectional view taken on the line 5, 5, of Fig. 3, looking in the direction indicated by the arrows, and Fig. 6 is an isolated detailed view partly in section and partly in elevation illustrating the mechanism for operatively connecting the wringer with the motor to drive the wringer in either direction as desired.

Similar reference numerals refer to similar parts throughout the several views.

As illustrated in the drawings the washing machine of my invention comprises a framework 10, preferably constructed of metal angles. Supported by the framework 10 is a sheet metal tank 11 conveniently provided with a suitable drain cock 12. As is most clearly illustrated in Fig. 2 the sheet metal forming the tank 11 is bent around a

suitable filler or fillers 13 of wood or other suitable material to lend rigidity to the tank and to form shoulders to engage the machine framework 10 to support the tank wholly or 5 in part. As is most clearly illustrated in Fig. 2 the tank 11 is provided with a cover 14, comprising two sections 14^a and 14^b hingedly connected. The cover 14 may be entirely removed from the tank when de- 10 sired. Carried by the portion 14^b of the cover is a deflector or baffle 15, the deflecting surface of which is preferably substantially concentric with the axis of the fabric container when the latter is in operating po- 15 sition. Disposed on the inner side of each one of the lateral walls of the tank 11 is a bracket 16 in the form of a metal angle riveted or otherwise secured to the tank. These brackets 16 are engaged by and sup- 20 port the deflector when the parts are in the positions illustrated in Fig. 2.

Carried by the inner faces of the lateral walls of the tank 11 are brackets 17 which serve as bearings for the rotatable cylinder 25 or fabric container illustrated at 18. The container 18 is preferably in the form of heads 18^a, 18^b, which carry the screen 18^c which forms the cylindrical surface of the container. The container is of course pro- 30 vided with a suitable door whereby the fabrics may be placed in and removed from the container, but I have not thought it necessary to illustrate such a door in the drawings. Each of the heads 18^a is provided 35 with an outwardly projecting trunnion 19 and loosely disposed around each one of said trunnions is the lower end of an arm 20, the arms 20 being provided with a connecting rod 21 which serves as a handle for the 40 ball or cylinder lifter. The connecting rod 21 may, of course, be provided with a sleeve of wood, or other material, as illustrated. Attention is directed to the fact that each of the brackets or bearings 17 is conformed to 45 present a substantially vertical section 17^a, a substantially horizontal surface 17^b near the upper end of the longer arm of the bracket, a substantially horizontal surface 17^c near the lower portion of the longer arm 50 of the bracket and a substantially vertical surface 17^d at the lower end of the shorter arm of the bracket.

The arms 20 of the bail-like fabric container lifter are provided with hubs 22 concentric with the trunnions of the fabric container or cylinder. These hubs are arranged to rest in the lower portions of their associated brackets 17 when the fabric container is in operating position. Attention is directed to the fact that formed integral with each of the hubs 22 is a lug 22^a. When the several parts are in the positions illustrated in Fig. 2 the weight of the bail-like lifter causes it to assume the position as shown in 5 the drawings, and thus the lugs 22^a coming

into engagement with the horizontal surfaces 17^a of the brackets 17 serve to lock the fabric container in its operating position. It will be understood that after dry clothes are placed in the fabric container and the same 70 is immersed in the solution in the tank the air entrained in the fabrics will tend to float the container unless some means is provided for locking the container in its operating position. 75

As will be hereinafter more fully explained the cylinder or fabric container is rotated and the clothes are washed by means of a stream of solution projected against and through the container. After the fabrics in the container have been washed the cover for the tank is removed and the bail-like lifter is moved to such a position that the lugs 22^a come into engagement with the short vertical surfaces 17^d of the brackets. 80 By so doing the container is unlocked and may be raised to the position shown in Fig. 4. After the container has been so raised the bail is permitted to assume the position shown in Fig. 4 and the lugs 22^a engaging 90 the horizontal surfaces 17^b of their associated brackets effectually serve to lock the container in its raised position. It will thus be seen that after fabrics have been washed the container may be raised to the position 95 shown in Fig. 4 to permit the articles to drain before they are removed from the container. Moreover this facilitates the removal of the fabrics from the container.

Suitably supported by the machine framework 10 is an electric motor 25 which may conveniently be provided with a shield 26 as illustrated in the drawings. As is most clearly illustrated in Fig. 5 the motor shaft 27 passes through a housing 28 and is provided with a worm 29 meshing with a worm-wheel 30 mounted upon a shaft 31 which extends from the housing 28 through an in- 100 closing tube 32 to another housing 33 where said shaft is provided with a bevel-gear 34. 105 The several housings may be formed integral with one another or otherwise as desired. Meshing with the bevel-gear 34, as most clearly illustrated in Fig. 1, is a bevel-gear 35 mounted upon a vertical shaft 36 which 110 has a relatively loose bearing in the housing 33. The shaft 36 extends upwardly from the housing 33 through a shaft housing 37 to a gear housing 38 supported by the framework of a wringer 39 which is mounted upon the tank as illustrated. As is most clearly illustrated in Fig. 6 the lowermost roller of the wringer extends into the housing 38 and is there provided with bevel-gears 40 and 41 fixed upon the shaft of the 115 wringer roller and adapted to be operatively engaged by the bevel-gear 42 fixed upon the upper end of the shaft 36. The bevel-gear 42 normally has a position whereby it is out of engagement with both of the gears 40 120

125 130

and 41 but it may be moved into engagement with either of them. The housing 38 is conformed to provide a chamber 43 in which is movably mounted a block 44 which 5 serves as a bearing for the upper end of the shaft 36. Formed in the block 44 is a channel 45. Mounted in the housing 38 is a shaft 46 provided at each end with an operating handle 47. It will be seen that this 10 shaft is conformed to have an eccentric middle portion 48 of reduced cross-section which passes through the channel 45 of the block 44. Thus it will be seen that by oscillating the shaft 46 the bevel-gear 42 may be 15 moved from its neutral position into engagement with either the bevel-gear 40 or the bevel-gear 41 or vice versa.

The shaft 27 of the motor 25 is operatively connected with a fan or screw propeller 49, the shaft of which has suitable bearings carried by the bottom of the tank 11. A suitable clutch is desirably interposed between the fan or propeller 49 and the shaft of the motor. However, I have 20 not deemed it necessary to illustrate such clutch mechanism in the present application. It will suffice to say that such clutch mechanism is actuated by means of an operating rod 50 most clearly illustrated in 25 Fig. 2.

As a result of the construction described when the fabrics to be washed have been placed in the cylinder or container and the usual soap and water solution has been 30 placed in the tank 11 to the proper depth, preferably to the top of the container when it is in operating position, the motor is started and the fan is operatively connected with the motor. The fan has a direction of 35 rotation such as to project a stream of water upwardly against the right-hand side of the cylinder or container (Fig. 2) with the result that the cylinder is rotated upon impact of the solution against the same. The 40 wire netting of the container permits a large portion of the water to project into and against the fabrics to be washed with the result that the fabrics are manipulated mechanically by the water thus projected, this 45 becoming an effective factor in washing the fabrics.

The rotation of the cylinder or fabric container 22 and the stream of water from the fan 49 move the fabrics toward the upper 50 part thereof and to the side of the container opposite the fan. The soap and water solution is projected vertically and strikes the deflector 15 and is turned so as to pass over the cylinder to the left and thus downward 55 upon the left-hand side of the cylinder (Fig. 2) and thence returning along the bottom of the tank to the suction side of the fan 49. That portion of the solution which is forced into the cylinder or fabric 60 container is drawn out of the cylinder at

the left-hand side thereof due to the suction created by the fan.

Having thus described my invention what I claim as new and desire to secure by Letters Patent of the United States is:

1. A washing machine, comprising in combination a tank adapted to contain a suitable washing solution, a removable cylindrical container, trunnions on the heads of said cylindrical container, a pair of 70 brackets carried in and by the tank arranged to support the container within the tank, a lifter for said container in the form of a bail, having its ends journaled upon said trunnions, an abutment on each of said brackets, and a fixed projection on each end of said bail like lifter adapted to engage one of said abutments to lock the container in position when the lifter is in a certain position, the engagement of said projections 80 with their coöperating bracket abutments as well as their release therefrom being effected by moving the bail-like lifter around its axis.

2. In a washing machine of the class described, a tank adapted to contain a suitable washing solution, a container for articles to be washed disposed within the tank but removable therefrom, means carried by the tank arranged to pivotally support the container for movement within the tank and a lifter for said container pivoted thereto and adapted to engage means fixed with respect to the tank to lock the container in its supporting means, said lifter 90 operable to lock or unlock the container by moving the lifter around its axis.

3. A washing machine, comprising in combination with a tank adapted to contain a suitable washing solution, a pair of oppositely disposed brackets within the tank, a cylindrical container for articles to be washed, adapted to be removably journaled in said brackets, and a lifter pivoted to said cylindrical container, said lifter adapted to be grasped to raise the container, but normally held by gravity in a certain position wherein it coöperates with the brackets to lock the container in position.

4. A washing machine, comprising in combination a tank adapted to contain a suitable washing solution and providing bearings for a removable container for articles to be washed, a container for the articles to be washed, a locking device pivoted to said container, normally assuming a certain position out of a vertical plane under the force of gravity, said locking device provided with a portion, adapted, when the said locking device is in said position, to engage means fixed with respect to the tank to lock the container in position, said locking device adapted to be grasped and moved to a position in a substantially vertical plane, in which last mentioned position it is released 115

from the means with which it coöperates to lock the container.

5. A washing machine comprising in combination a tank arranged to contain a suitable washing solution, a removable container for articles to be washed disposed within the tank, means carried by the tank arranged to support said container for movement on a horizontal axis, and a lifter pivoted to said 10 container, said lifter when in normal position engaging the supporting means to lock the container in position, but adapted to be grasped to release the container and raise the same, the lifter being operable to effect 15 its engagement with or disengagement from the supporting means by moving the lifter around its axis.

6. A washing machine, comprising in combination a tank, a container for articles to 20 be washed, means carried by the tank arranged to pivotally support the container for movement about a horizontal axis, and a lifter pivoted to said container, normally assuming a certain position, whereby it 25 operates with the supporting means to lock the container in position, said lifter being operable to release the container by moving the lifter around its axis.

7. A washing machine, comprising in combination a tank, a pair of oppositely and vertically disposed brackets carried by the tank, each of said brackets being of substantial U shape, but having one leg thereof extended to form a guide, a container for articles to be washed, arranged to be removably journaled in said brackets, a bail-like lifter for said container, normally coöperating with the supporting brackets to lock the container in operating position, but adapted to 35 be grasped to release the container and raise the latter along the guides afforded by the extended legs of said U shaped brackets.

8. A washing machine, comprising in combination a tank, a pair of oppositely disposed brackets within the tank, each of said brackets being of substantially U shape, and provided with two shoulders at different heights upon one of the legs thereof, a container for articles to be washed, removably 45 journaled in said U shaped brackets, and a lifter for said container, normally coöperating with the lowermost pair of said bracket shoulders to lock the container in operating position, but arranged to be grasped to raise 50 the container to a position such that the lifter in a similar manner coöperates with the uppermost pair of said bracket shoulders, to lock the container in raised position.

9. A washing machine, comprising in combination a tank, a pair of oppositely disposed U shaped brackets carried within the tank, a container for articles to be washed,

removably journaled in said brackets, each of said brackets having one leg thereof conformed to present two shoulders at different heights with a guiding surface between them, and a lifter pivoted to said container, provided with portions normally coöperating with the lowermost pair of bracket shoulders to lock the container in position, 65 but adapted to be grasped to release the container and raise the same along the guiding surfaces intermediate the bracket shoulders, said lifter also arranged to coöperate with the uppermost bracket shoulders to lock the 70 container in raised position, the lifter being operable to effect its engagement with or disengagement from the bracket shoulders by moving the lifter around its axis.

10. A washing machine, comprising in combination a tank adapted to contain a suitable washing solution, a pair of oppositely and vertically disposed U shaped brackets carried by the tank, each of said brackets having one leg thereof conformed to present two shoulders at different heights with a guiding surface between them, a cylindrical container for articles to be washed, journaled in said brackets for movement around a horizontal axis, the heads of said 80 container provided with trunnions, a bail-like lifter having the ends thereof journaled on said trunnions, and being there provided with lugs arranged to coöperate with the bracket shoulders to lock the container in 85 either its operating position or a raised position, as desired, the bail-like lifter operable to effect its engagement with or disengagement from the bracket shoulders by moving the lifter around its axis.

11. In a washing machine of the class described, in combination with a container for articles to be washed, a tank arranged to contain a suitable washing solution and to inclose said container, means for pivotally 105 supporting the container for operation around a horizontal axis, and a bail-like lifter pivoted to said container at its axis of rotation, said bail-like lifter normally assuming a position whereby the handle portion thereof rests against an adjacent wall of the tank, and when in such position co-operating with means fixed with respect to the tank to lock the container in position, said bail-like lifter movable on its axis to 110 release the container and adapted to be grasped to raise the container.

In witness whereof, I hereunto subscribe my name this 9th day of January, A. D. 1915.

GEORGE H. MYRICK.
